UNITED STATES PATENT OFFICE.

DAVID RUSSAKOV, OF CHICAGO, ILLINOIS.

HASP AND STAPLE DEVICE.

1,369,937.

Specification of Letters Patent.

Patented Mar. 1, 1921.

Application filed November 19, 1919. Serial No. 339,195.

To all whom it may concern:

Be it known that I, DAVID RUSSAKOV, a citizen of the United States, residing at Chicago, Cook county, Illinois, have invented certain new and useful Improvements in Hasp and Staple Devices, of which the following is a specification.

My invention relates to hasp-and-staple devices. Its principal object is to provide simple and effective self-contained means for holding the hasp upon the staple in such manner that the hasp may be readily applied to and released from the staple as desired, while maintaining the capacity of the 15 staple for holding a separable locking device, such as a padlock, for securing the hasp and staple together.

In the accompanying drawings, which form a part of this specification, I have 20 illustrated these improvements in what I now consider to be their most advantageous form, but I contemplate various changes and modifications therefrom within the scope of the appended claim. In these 25 drawings Figure 1 is a face view of the device in locked condition; Fig. 2 is a medial longitudinal section of the hasp and locking element and a side view of the hasp showing the operation of applying or re- 30 moving the hasp; Fig. 3 is a face view of the hasp alone; and Fig. 4 is a face view of the staple and locking element thereon.

The hasp 10 having the butt 11 and the hinge 12, as well as the staple 14 rigidly 35 secured upon the plate 15, the hasp having a slot-like opening 16 for the staple, are according to well known practice, and these particular forms of hasp and staple are here shown merely as convenient types for 40 illustration.

Upon the staple 14 I mount loosely the hasp-locking element 17, which is shown as a flat disk having a substantially central hole 18, the staple 14 passing through this 45 hole, and the element 17 being capable of easy sliding movement throughout the extent of the substantially U-shaped exposed portion of the hasp. Where the staple is of the ordinary kind having free pointed 50 ends adapted to be driven into the wood this element 17 may be an ordinary washer such as is commonly used with bolts and nuts; but where the staple 14 is rigidly secured upon a plate as 15 this locking element 17 is 55 provided with a split or cut at 19 whereby the washer-like disk may be opened there-

and placed upon the staple and then re-formed into its substantially flat shape. The locking element 17 is therefore permanently held upon the staple and is always 60 available for use, this feature avoiding the annoyance due to the loss of separate means for holding the parts together.

The slot-like opening 16 in the hasp is modified at 20 and 21 by the provision of 65 an enlargement thereof at a localized area, which localized area is substantially midway of the ends of the slot 16 where the staple has a rounded top, where a form of element 17 is employed as shown, and where the slot 70 16 is merely of such length as to accommodate readily the staple. The enlargements 20 and 21 are in the form of recesses extending through the thickness of the hasp there and away from the slot 16 in substantially opposite directions, and the width and 75 length of these enlargements 20 and 21 are such that when the hasp-locking element 17 is directed toward these enlargements the hasp may be placed upon the staple or removed therefrom as soon as edge portions 80 of the element 17 pass through these enlargements 20 and 21.

A feature of peculiar importance is in the fact that when the hasp has been placed 85 upon the staple the element 17 invariably assumes some other position than that of its direction toward the openings 20 and 21, and on attempting to pull the hasp away from the staple the element 17 becomes an 90 effective obstruction thereto on one leg or the other of the staple, for instance as shown in Fig. 1. The locking effect is had whatever the bodily position of the combined hasp-and-staple may be, and the de- 95 vice is therefore of marked importance in connection with boxes the lids of which it is desired to hold securely, notwithstanding that the boxes may be turned over from time to time on all sides or ends, as in han- 100 dling.

In applying the hasp to the staple the operator grasps the locking element 17 with one hand and directs it toward the openings 20 and 21 while the hasp is being applied 105 with the other hand. As soon as edge portions of the element 17 have entered the recesses 20 and 21 the hasp readily slips upon the staple. In removing the hasp the element 17 is similarly turned by hand so as to 110 enter the recesses 20 and 21, and thereupon the hasp may be readily withdrawn.

The hasp-and-staple parts may be made of the usual materials and according to methods well understood. The locking element 17 is preferably a metal disk or plate 5 similar to the ordinary washer in the construction shown.

I claim:

A hasp-and-staple device comprising a staple, a hasp having a slot-like opening 10 therethrough for the staple, and a hasp-locking element comprising a substantially circular flat disk-like plate having a hole

substantially centrally therethrough and slidably mounted on said staple with the staple in said hole, the hasp being provided 15 with a pair of substantially oppositely disposed recesses extending from said slot-like opening, said recesses being formed to admit of the passage therethrough of edge portions of said hasp-locking element when 20 said element is directed edgewise toward said recesses in applying the hasp to or removing it from said staple.

DAVID RUSSAKOV.
